LIPSTICK CASE

Albert Gelardin, New York, N. Y.

Original application May 3, 1947, Serial No. 745,701. Divided and this application October 15, 1948, Serial No. 54,625

15 Claims. (Cl. 206—56)

1

This invention relates to improvements in lipstick cases, and, more particularly, to novel propel-repel cases embodying coil compression springs contained in and actuated by a rotatable base member. This application is a division of my application Serial No. 745,701, filed May 3, 1947, for Lipstick cases.

In my prior application Serial No. 625,801, filed October 31, 1945, I disclosed and claimed a lipstick case consisting of an outer shell with a rotatable base attached thereto, the shell having a cage or fenestrated retaining device fitted therein to serve as a retainer for a coil compression spring, to the free end of which a cup is attached, the cup receiving a lipstick, and movable in the shell by the spring. In this form, the cup rotates with the spring as the latter is actuated by the rotatable base. Under such conditions, the form of the cup and of the lipstick carried therein is essentially restricted to a circular or cylindrical type.

I have now found that lipstick cases of the compression spring actuated type can be utilized in cross-sectional shapes of any desired contour, and so constituted and arranged that the lipstick cups are prevented from rotation, yet are freely movable along the longitudinal axis of the device.

The improvements of the present invention will be more clearly understood by reference to the accompanying drawings, in which certain preferred embodiments are shown, by way of illustration only, as it is not intended to be limited to the forms here shown, except as such limitations are clearly imposed by the appended claims.

In the drawings like numerals refer to similar parts throughout the several views, of which

Fig. 1 is an elevation of a lipstick case of square cross section;

Fig. 2 is a vertical section taken on line 2—2 of Fig. 1;

Figs. 3, 4 and 5 are horizontal cross sections taken on lines 3—3, 4—4 and 5—5 of Fig. 2;

Figs. 6 and 7 are elevations of a lipstick case of diamond cross section viewed along the major and minor axes, respectively;

Figs. 8 and 9 are top views and bottom views, respectively, of the lipstick case of Figs. 6 and 7;

Fig. 10 is a vertical section of the case as illustrated in Fig. 6;

Fig. 11 is a vertical section taken on line 11—11 of Fig. 10, and

Fig. 12 is a horizontal section taken on line 12—12 of Fig. 10.

The lipstick cases of the present invention consist essentially of an outer, non-curvilinear shell

5 with a rotatable base attached thereto, the rotatable base having a depression therein or forming a well to receive a substantial portion of a coiled compression spring. A barrier is included in the hollow base at an appreciable distance from the bottom, of such dimensions, and so oriented, that the helical turns of the spring will have normal bearing engagement against the barrier and yet can thread their way past the barrier without distortion or binding. The bottom of the spring is preferably loosely disposed within the base and is so configured and arranged that the lower end of the spring cannot thread its way past the barrier. The upper end of the spring is attached 10 to a lipstick cup which is slidably mounted within the shell, the cup being so mounted within the shell that it cannot rotate. The non-rotatability of the cup is assured by the particular shape of the shell and of the cup.

15 In operation, the lipstick case will be actuated by rotating the base, which during its rotation collects or releases a certain amount of the coiled spring from the cavity within the base, thereby causing the cup to rise or descend within the shell 20 or casing.

25 The lipstick cases herein are characterized by (1) simplicity of parts; (2) simplicity of assembly; (3) unusual shaped pieces of cosmetics which are more suitable for application to the lips.

30 Where unusual shapes of lipsticks are used, the swivel type cases herein will elevate and lower the lipstick mass without rotating the same in its longitudinal reciprocating travel. As will be 35 shown more in detail herein, and in my said parent application, cosmetics or lipstick masses can be made in tear-drop cross-section, diamond cross-section, and square cross-section, so that as they are used, there will always be a point or edge available for application to the lips to permit the forming of a sharply delineated line on the lips.

35 Another and important advantage of the devices herein, and particularly with reference to the non-circular containers, resides in the fact that the shape of the container permits the base to be snapped into place with great ease. An additional advantage of the cup-base construction resides in the fact that all the spring pressure, 40 when the spring is compacted below the barrier pin, does not tend to push the base away from the sleeve. Furthermore, in the present case, the free swiveling of the base acts to let the spring compress and decompress without distortion.

45 Considering the individual structures more in

2

detail, the form illustrated in Figs. 1 to 5 will be considered first. According to this form of the invention, the lipstick case comprises a non-curvilinear or polygonal shell or case 60, a bottomless, rotatable cylinder 21, a cup 30a and spring 40.

The base 20 comprises a generally cylindrical bottomless body portion 21 with a shouldered flange extension 23'. The collar or body portion 21 and the cover plate 66 define a central space or cup 25 into which is freely received the bottom compressed portion 41 of spring 40. A barrier pin 26 is fitted in a diameter of the body 21, and oriented at such an angle as to equal one-half of the pitch of the unexpanded or free turns 42 of the spring. At its upper end 43 the spring is secured to cup 30a by means of a hollow rivet 44. The free end 45 of the spring may be bent as shown to insure its engagement and retention by the barrier pin 26 when the spring is rotated to its full expanded length. Normally, the full, expanded length of the spring will exceed the overall length of the casing 10, so as to insure that the tip of the lipstick carrier or cup 30 will project through the open mouth or aperture 18 of the casing.

In the form shown in Figs. 1 to 5, the casing 60 is a tubular member of square cross-section having sides 61 and an open top 62 with a peened-in or shouldered edge 63. The walls 61 normally terminate in central bottom portions 64 and depending angular edges or skirts 65. A flat cover plate 66 is provided with upstanding corner posts 67 which are fitted into and engage the skirts 65 and to which they are secured, in any suitable manner, as by pins or screws 68. Where desired, the depending angular edges or skirts may be dispensed with, and the corner posts will be lengthened to extend up into the corners of the tubular body section. The inner surfaces or edges of the studs or posts 67 are conformed to the periphery of flange 23' of the rotatable member 20 to permit the latter member to rotate freely therein. In the form shown, the cup 30a is provided with sides 31a having spaced transverse ridges 33a engaging the walls of the casing. The bottom 32a will be secured to the spring 40 in the usual manner by hollow rivet 44. Thus it will be seen that the desirable advantages of a freely mounted compression spring engageable by a rotatable member to actuate a propel-repel lipstick cup in a lipstick case of square cross-section is readily effected by incorporating the principles of the present invention.

In the form shown in Figs. 6 to 12, a lipstick casing 80, of generally diamond cross-section, has opposed edges 81, 81', defining a major axis, and 82, 82', defining a minor axis, with sides 83 formed in and between the said several edges. The top of the casing is peened over, as indicated at 84, and the edges 81, 81', are provided with skirted extensions, designated generally by the numeral 85, to receive opposed studs 86 of a bottom closure plate 87 which is secured to the casing by the usual pins or screws 68. The plate 87 is cut away, as indicated at 89, to permit the knurled edge or flange 23 of rotatable member 20 to extend a sufficient distance to be grasped by and rotated between the fingers. The cup 30c has the usual spacing ridges 33c and bottom 32c secured by hollow rivet 44 to spring 40.

It will now be appreciated that there has been provided novel lipstick cases of the propel-repel type which are adapted to use lipstick masses of varying cross-section, yet which use controlling or operating mechanism of uniform structure and

mounting and which permit the variation of casing parts and lipstick carriers without requiring any fundamental variation in the operating mechanism. It will also be appreciated that there has been provided a novel lipstick case and operating mechanism which is spring-driven, yet in which the spring is never exposed to conditions tending to bind or cause the same to jam so that the spring, being freely rotatable in the casing, under operating conditions, will not twist or become distorted and break during use.

What is claimed is:

1. A lipstick holder comprising a non-curvilinear, tubular casing, a rotatable base, a non-rotatable lipstick carrier mounted for reciprocation in the casing, a compressible spring reciprocable with and fixed to the carrier and nested in the rotatable base, and restraining means for the spring in the base and maintaining the subjacent spring in compressed condition.
2. Rotatable base member according to claim 1 which is an open-ended cylinder.
3. Base member construction according to claim 2 in which the bottom of the open cylinder is closed by a plate secured to the bottom of the casing.
4. Base member according to claim 1 in which restraining means for the spring comprises a barrier pin.
5. A lipstick holder according to claim 1, in which the casing is non-circular in cross-section.
6. A lipstick holder according to claim 5 in which the tubular casing is polygonal in cross-section.
7. A lipstick holder according to claim 6 in which the tubular casing is rectangular in cross-section.
8. A lipstick holder according to claim 7 in which the tubular casing is square in cross-section.
9. A lipstick holder according to claim 1 in which the tubular casing is diamond-shaped in cross-section.
10. In a lipstick holder comprising a tubular casing, a rotatable base, a non-rotatable lipstick carrier conformed to and mounted for reciprocation in the casing, a compressible spring fixed to the carrier and nested in the rotatable base, and restraining means for the spring formed in the base and maintaining the subjacent spring in compressed condition, the improvements comprising a diamond-shaped casing, a rotatable base being an open-ended cylinder with an exposed actuating flange, a cover plate over the flanged end of the base and secured to the casing, and a helical groove in the top portion of the base comprising a complete turn conforming to the pitch angle of the freely expanded spring and maintaining the subjacent coils of the spring under compression.
11. In a lipstick holder comprising a tubular casing, a rotatable base, a non-rotatable lipstick carrier conformed to and mounted for reciprocation in the casing, a compressible spring fixed to the carrier and nested in the rotatable base, and restraining means for the spring formed in the base and maintaining the subjacent spring in compressed condition, the improvements comprising a diamond-shaped casing, a rotatable base being an open-ended cylinder with an exposed actuating flange, a cover plate over the flanged end of the base and secured to the casing, and a barrier pin in the top portion of the base and transversely thereof and at an angle equal to one-half the free pitch angle of the spring and main-

taining the subjacent coils of the spring under compression.

12. In a lipstick holder comprising a tubular casing, a rotatable base, a non-rotatable lipstick carrier conformed to and mounted for reciprocation in the casing, a compressible spring fixed to the carrier and nested in the rotatable base, and restraining means for the spring formed in the base and maintaining the subjacent spring in compressed condition, the improvements comprising a square-shaped casing, a rotatable base being an open-ended cylinder with an exposed actuating flange, a cover plate over the flanged end of the base and secured to the casing, and a helical groove in the top portion of the base comprising a complete turn conforming to the pitch angle of the freely expanded spring and maintaining the subjacent coils of the spring under compression.

13. In a lipstick holder comprising a tubular casing, a rotatable base, a non-rotatable lipstick carrier conformed to and mounted for reciprocation in the casing, a compressible spring fixed to the carrier and nested in the rotatable base, and restraining means for the spring formed in the base and maintaining the subjacent spring in compressed condition, the improvements comprising a square-shaped casing, a rotatable base being an open-ended cylinder with an exposed actuating flange, a cover plate over the flanged end of the base and secured to the casing, and a barrier pin in the top portion of the base and transversely thereof and at an angle equal to one-half the free pitch angle of the spring and maintaining the subjacent coils of the spring under compression.

14. In a lipstick holder comprising a tubular casing, a rotatable base, a non-rotatable lipstick carrier conformed to and mounted for reciproca-

tion in the casing, a compressible spring fixed to the carrier and nested in the rotatable base, and restraining means for the spring formed in the base and maintaining the subjacent spring in compressed condition, the improvements comprising a diamond-shaped casing, a rotatable base being an open-ended cylinder with an exposed actuating flange, a cover plate over the flanged end of the base and secured to the casing, and a combination helical groove and barrier pin and engaging a coil of the spring at an angle equal to one-half the pitch angle of the freely expanded spring and maintaining the subjacent coils of the spring under compression.

15. A lipstick holder comprising a tubular casing of non-curvilinear cross-section, said casing having an inwardly flanged top defining an opening for receiving a lipstick mass in use position, a lipstick carrier in the case and conformed thereto, means for reciprocating the carrier comprising a helical compression spring having one end fixed to the carrier and the other end freely received in an open-bottomed, rotatable cylindrical actuator, depending aprons at the bottom of the casing, a base plate secured to said aprons over the bottom end of the actuator, the rotatable actuator being mounted for rotation in the casing and between the bottom of the casing and the base plate, the said actuator including a flanged bottom for manually rotating same, the cylindrical actuator being open and including means to compress a contained helical compression spring with the coil turn engaged thereby held at the free pitch angle of the spring and the coil turns between the carrier and the rotatable actuator being freely expanded.
